CASING FOR EXIT LIGHT

William F. Roy, Danbury, Conn., assignor to Tru-Lite Corporation, Danbury, Conn., a corporation of Connecticut

Application April 20, 1949, Serial No. 2,161

Term of patent 3½ years

(Cl. D72—1)

To all whom it may concern:

Be it known that I, William F. Roy, a citizen of the United States, residing at Danbury, county of Fairfield, and State of Connecticut, have invented a new, original, and ornamental Design for a Casing for Exit Light, of which the following is a specification, reference being had to the accompanying drawing, forming part hereof, in which:

Figure 1 is a perspective view of a casing for exit light showing my new design.

Fig. 2 is an end elevational view thereof; and Fig. 3 is a bottom plan view thereof.

The back of the casing is plain.

The dotted lines shown in the drawing are for illustrative purposes only.

I claim:
The ornamental design for a casing for exit light, as shown and described.

WILLIAM F. ROY.
